UNITED STATES PATENT OFFICE.

JOHN PERCIVAL CULLON, OF TORONTO, ONTARIO, CANADA.

FLUE-CLEANER.

1,076,869.

Specification of Letters Patent.

Patented Oct. 28, 1913.

Application filed April 10, 1913. Serial No. 760,211.

To all whom it may concern:

Be it known that I, JOHN PERCIVAL CULLON, of the city of Toronto, in the county of York, in the Province of Ontario, Canada, have invented certain new and useful Improvements in Flue-Cleaners, of which the following is the specification.

My invention relates to improvements in flue cleaners, and the object of the invention 10 is to devise a flue cleaner, which will pass collapsed portions and welded joints of a flue, in which means are provided for preventing the catching of the cleaner on the edge of the flue at the commencement of the 15 return stroke, in which the plugging of the cleaner in the flue is prevented, in which the shearing power of the cutting blades of a flue cleaner is increased, and in which the cutting edges of such blades are not dulled 20 by wear and in which easy access to the rivets is provided for the purpose of repair, and it consists essentially of the cleaner rod, a conical head secured at one end of the rod, a bell shaped head located intermediate 25 of the length of the rod, arched springs connecting the conical and bell heads together, cutting blades V-shaped in form secured to the arched springs, a securing nut threaded on the cleaner rod and a compression spring extending between the nut and the bell head as hereinafter more particularly explained.

Figure 1, is a perspective view of my cleaner in position in the flue, showing the 35 flue in section. Fig. 2, is a longitudinal section through the cleaner and flue. Fig. 3, is a cross section through the cleaner and flue.

In the drawings like letters of reference 40 indicate corresponding parts in each figure.

A is the cleaner rod provided with an outer threaded end A' and an inner threaded end A² connected by suitable union joints A³ to a handle A⁴, (a small portion only of 45 which is shown).

B is a conical head preferably hexagonal in form and provided with a threaded orifice B' threaded on to the threaded end A' of the rod A.

50 C is a head provided with an opening C' through which the rod freely extends. As shown in Fig. 2, the opening C is slightly larger in diameter than the diameter of the rod A. The head C is provided with a se-

ries of peripheral recesses C² terminating 55 at their inner ends in peripheral orifices C³.

D is a nut threaded on to the rod A.

D' is a washer bearing against the nut and D² is a compression spring extending between the washer D and the outer or 60 small end of the bell head C.

E are arched springs preferably three in number and secured at one end to the alternate faces of the hexagonal head B by the rivets E'. The opposite ends of the arched 65 springs E are passed through the openings C³ into the recesses C² in which they are secured by the rivets E².

F are V-shaped cutting blades, the apexes of which are turned inwardly at F', the opposite sides of each cutting blade being provided with inwardly beveled portions F² and F³ and a central exterior end portion hollowed out at F⁴ thereby forming peripheral cutting edges F⁵ and F⁶. It will thus 70 be seen by reason of the beveled portions F² and F³ the cutting edges F⁵ and F⁶ will 75 remain sharp, and in fact are sharpened by the wear against the inner periphery and the flue.

F⁷ are rivets connecting the wider end of each of the cutting blades to the arched springs E.

2 is a flue.

Having now described the principal parts 85 involved in my invention I shall briefly describe the operation of the same.

It will thus be understood that the flue cleaner is thrust longitudinally into the flue. If the flue is collapsed at any portion or 90 there is a weld, which decreases the interior diameter of the flue the arched springs E and compression spring D² give sufficiently to allow the cleaner to pass such reduced portion. If it is necessary to adjust the cleaner 95 to different diameters of flues all that is necessary is to tighten the nut D against the compression spring D² forcing the head C longitudinally and the arched springs outwardly carrying the cutting edges F⁵ and 100 F⁶ outwardly against the interior periphery of the flue. Also by reducing the size of the front head B there is no danger of the flue cleaner clogging within the flue by reason of the scale and other matter concreting around the cleaner and plugging it up. It will also be understood that the arched springs E are so arranged that there 105

is an open space opposite each spring and that therefore should any of the cutting blades become loose and require removal the rivets F^e may be tightened without the aid of any special tool or the rivet heads cut off if it is desired to entirely remove the blade.

By forming the blades V-shaped a double cutting edge is formed, whereby an obstructing portion of blade sticking to the interior of the flue when passing the cleaner in one direction is cut at an angle and is cut at an opposite angle when passing the cleaner in the opposite direction, thereby more easily severing the scale than would be the case if the cutting blades cut at the same angle both during the forward and return stroke of the cleaner.

From this description it will be seen that I have devised a very simple form of flue cleaner which will readily pass collapsed portions of the tube or welded joints, which will readily return into the flue at the commencement of the return stroke of the

cleaner, which will not be liable to plug in the flue and which will have increased shearing power and in which the blades are not liable to become dulled by use.

What I claim as my invention is—

1. In a flue cleaner a series of cutting blades arranged end to end in circumferentially and curved eccentric form, said blades being wider at one end and tapering to V-shape at the opposite end thereof and a support for said blades.

2. In a flue cleaner, the combination of heads with arched springs connecting the heads together, a series of cutting blades secured to the arched springs, curving circumferentially and concentrically to the cleaner, said blades being wider at one end and tapering to V-shape at the other end thereof, said blades being arranged end to end.

JOHN PERCIVAL CULLON.
